ASSIGNORS TO MIEHLE PRINTING PRESS AND MANUFACTURING COMPANY, OF
CHICAGO, ILLINOIS, A CORPORATION OF ILLINOIS.

MOUNTING AND OPERATING MECHANISM FOR RECIPROCATING BEDS OF PRINTING PRESSES.

Application filed March 3, 1921. Serial No. 449,529.

To all whom it may concern:

Be it known that we, BURT D. STEVENS and EDWARD F. DUDLEY, citizens of the United States, and residents, respectively, 5 of the city of Evanston, county of Cook, State of Illinois, and village of Oak Park, county of Cook, and State of Illinois, have invented certain new and useful Improvements in Mountings and Operating Mechanisms for Reciprocating Beds of Printing 10 Presses, of which the following is a specification.

The main object and leading purpose of present invention is the provision of novel 15 and effective means for reciprocating the printing-form bed of a printing-press and so supporting and backing up the bed that the strains to which it is subjected by its coaction with the impression-cylinder will 20 be well distributed and will not be imposed solely or unduly on the walls of the grooves or guideways in which the edge portions of the bed slide and by which they are guided in their movements.

25 One aim of the invention is to provide a plurality of rollers back of and engaging tracks on the bed whereby to relieve the guideways for the latter in substantial manner from the pressure imposed on the bed incident to and during the printing operation.

It is desirable that some of such backing-up or strain-relieving rollers shall be near the middle of the bed, that is midway between the guideways, and to accomplish this 35 a compact driving or reciprocating mechanism for the bed is desirable, thus preventing the inner rollers from necessarily being excessively separated from one another.

40 To this and other advantageous ends a unique and efficient bed sliding mechanism has been devised which occupies but comparatively small space crosswise the machine hence permitting the inner pressure- 45 rollers being placed nearer to one another than would otherwise be possible.

In the accompanying drawing, forming a part of this specification, and throughout the several views of which like reference 50 characters refer to the same parts, a desir-

able and preferred embodiment of the invention has been illustrated.

In this drawing:

Figure 1 is a plan view of the improved structure;

Figure 2 is a partial vertical section on an enlarged scale showing the relation to one another of the spiral-gears, the connecting-rod, and other parts;

Figure 3 illustrates one of the eccentric 60 mountings for one of the backing-up rollers;

Figure 4 is an end view of the member depicted in Figure 3; and

Figure 5 shows a ball-bearing backing-up 65 roller.

By reference to the drawing it will be seen that the machine includes a frame 10 having opposed, registered, vertical guideways or grooves 11, 11 accommodating the upright edge portions of a reciprocating printing-form bed 12 which is in cooperative relation with a companion impression-cylinder 13, the several parts being shown somewhat diagrammatically.

Such a bed is subjected to considerable strain and pressure during the printing operation and unless some means are provided to overcome such objectionable feature, the walls of the guideways undergo excessive 80 pressure and wear, the bed itself possibly being slightly deformed under the relatively high strains imposed on it.

Accordingly the back of the bed is equipped with or has fastened to it a plurality of vertically-arranged flat tracks or bars 14, 15, 16, and 17, four in the present instance, but the exact number is of minor importance.

It is desirable, however, that they shall be 90 well and fairly equally spaced throughout the surface or area of such bed to secure an even distribution of the strains.

Bearing on these tracks are a corresponding number of backing-up rollers 18, 19, 20 95 and 21 each revolvably mounted on its individual shaft 22 supported in a pair of brackets or arms 23, 24 forming part of or secured to the frame.

In order that such rollers may be sepa- 100

rately adjustable toward and from their respective tracks, whereby each may do its proper share of the work imposed on them, each shaft 22 has a central portion 25 on 5 which the roller is revolvably mounted and two eccentric parts 26 and 27 fitted in cylindrical apertures in the brackets or arms.

One end of the shaft is provided with a series of notches 28, any one of which may 10 accommodate a portion of the head of a retaining screw or pin, not shown, and by angularly adjusting these eccentric sections in the bearings the corresponding roller may be shifted toward and from the bed as 15 occasion requires.

The means for reciprocating the bed comprises the following cooperating instrumentalities:

Two, stationary, spaced, upright racks 29 20 and 30 with oppositely-inclined teeth are fastened to the frame 10 and similar racks 31 and 32 in register with the first pair are secured to the back of and slide with the vertically reciprocating bed.

Between the frame racks and bed racks and in proper mesh with one of each, is a pair of spiral-gears 33 and 34, with reverse-inclined teeth, cut on the opposite, enlarged, end portions of a single piece of 30 metal, the intermediate, cylindrical part 35 of which between the gears forms a bearing or shaft for the upper end of a connecting-rod or link 36 actuated from below by a crank-shaft, not shown.

Thus as the gears are forced to travel up and down by the action of the connecting-rod, and, by reason of their meshing with the stationary racks, they, by their combined, bodily travel along the racks and 40 their rotation about their own axes, compel or occasion the reciprocation of the bed, giving to the latter a length of stroke or travel twice that of the movement of the connecting-rod.

It is to be observed that the teeth of the pairs of racks and those of the gears are oppositely inclined and as the gears are rigidly united together, they are effectively prevented from shifting axially out of position or alignment with their racks in either direction, and, since the upper end of the connecting rod has no other connection than with the shaft of the gears as shown, such gears and racks constitute the sole 55 guiding means for that end of the connecting-rod. No end thrust bearings are employed other than the sloping teeth of the gears and racks.

Stated somewhat differently, the herring-bone racks and gears are the only means necessary to guide the upper end of the connecting-rod, one set of racks and their companion gear preventing shifting of the parts in one direction, while the other pair of 65 racks and their gear with oppositely in-

clined teeth eliminate the possibility of the parts being displaced in the opposite direction.

Such an arrangement, as will be obvious, produces a particularly compact construction crosswise the bed, and hence allows the inner backing-up rollers to be placed desirably nearer one another than would otherwise be possible.

To assure that the gears and racks shall be always in proper mesh, the outer side faces of the gears have fixedly and concentrically mounted thereon, as by suitable screws, rollers 37 and 38 with cylindrical surfaces coinciding with the pitch-circles of 75 the gears.

The peripheries of such rollers bear at their opposite sides on flat, vertical track-bars 39 and 40, two of the latter being fixed to the frame, the other two being carried by 85 the bed, the active faces of such bars being in register with the pitch-lines or pitch-planes of the corresponding racks, thus insuring proper meshing of the gears and racks under all circumstances.

The backing-up rollers 18, 19, 20, and 21 may be of any usual type, but to reduce friction and to diminish as much as possible the inertia of the reciprocating elements and those which change their direction of movement, it is desirable to use backing-up rollers of special construction. For these elements we preferably employ the ordinary anti-friction ball-bearings 41 using the outer ball-race member 42 as the 90 roller, such element readily turning on the supporting balls and having but comparatively little weight or mass.

Those skilled in this art will understand that while one preferred embodiment of 105 the invention has been illustrated and described in detail, the invention is susceptible of a variety of embodiments, differing more or less in mechanical features but all incorporating the main underlying 110 principles of structure and modes of operation characteristic of the invention. All such equivalent structures are comprised within the scope of this invention as defined by the appended claims.

We claim:

1. In a printing-press, the combination of a frame, a printing-form bed mounted for reciprocation in guideways in said frame, an impression-cylinder cooperating with said bed, means to reciprocate said bed comprising a pair of stationary racks with oppositely-inclined teeth mounted on said frame, a pair of similar racks fixed to and slidable with said bed, a pair of spiral-gears secured together and each in mesh with one of each of said pairs of racks, means to effect the reciprocation of the bed by causing the bodily travel of the gears along the stationary racks, pitch- 120

125

- plane tracks in register with said racks, pitch-circle rollers registering and rigid with said gears and adapted to travel on said tracks to assure proper meshing of the 5 gears and racks, and a plurality of backing-up rollers co-acting with the rear of said bed to relieve said guideways from at least a part of the strains imposed on the bed, substantially as described.
- 10 2. In a printing-press, the combination of a frame, a printing-form bed mounted for reciprocation in guideways in said frame, an impression-cylinder cooperating with said bed, means to reciprocate said bed 15 comprising a pair of stationary racks with oppositely-inclined teeth mounted on said frame, a pair of similar racks fixed to and slidable with said bed, a pair of spaced spiral-gears connected together by a shaft and each intermeshing with one of each of 20 said pairs of racks, and a connecting-rod rockingly mounted on said gear-shaft between the gears and adapted to effect the reciprocation of the bed by causing the bodily travel of the gears along the stationary 25 racks, pitch-plane tracks in register with said racks, pitch-circle rollers registering and rigid with said gears and adapted to travel on said tracks to assure proper meshing of the gears and racks, and a plurality of backing-up rollers coacting with the rear of said bed to relieve said guideways from at least a part of the strains imposed on the bed, substantially as described.
